Attorneys.

Inventor

UNITED STATES PATENT OFFICE.

WILLIAM J. BARRETT, OF BRIDGEPORT, CONNECTICUT.

ILLUMINATED TARGET.

Application filed November 14, 1923. Serial No. 674,752.

To all whom it may concern:

Be it known that I, WILLIAM J. BARRETT, a citizen of the United States, residing at Bridgeport, county of Fairfield, State of Connecticut, have invented a new and useful Illuminated Target, of which the following is a specification.

This invention relates to leveler's rods, and particularly to a target for such rods, and has for an object to provide an improved target which may be used in poor lights or even in darkness.

It is also an object of the invention to provide a device of this character which is very simple in construction and to which the ordinary electric flash lamp may be easily attached and detached for illuminating the target.

With the foregoing and other objects in view, I have devised the construction illustrated in the accompanying drawing, forming a part of this specification, similar reference characters being employed throughout the various figures to indicate corresponding elements. In this drawing,

Fig. 1 is a side elevation of a portion of a leveler's rod and my improved target applied thereto, a portion of the front wall of the target being broken away to more clearly show the construction.

Fig. 2 is a similar view of a portion of a target showing a slightly different means for securing the flash lamp to the target, and

Fig. 3 is a transverse section substantially on line 3—3 of Fig. 1.

In this drawing 10 represents a portion of any desired type of leveler's rod graduated in the usual manner, as shown at 11. Mounted to slide on this rod is a target 12 upon which the leveler trains his instrument for reading the levels in the usual manner. This target has in the front wall thereof a rectangular opening 13 through which the graduations 11 are visible and is also provided with the usual horizontal zero line 14. The usual clamping screw 15 is provided for clamping the target to the rod in any desired position.

In using these instruments in poor lights as in cellars, on dark days or in mines, it is often very difficult for the man operating the instrument to see the target and to train this instrument on the target. To overcome this difficulty I have provided the target with a chamber 16 on one side of the rod and

provide in the front wall of this target a cross 17. This cross is preferably formed by cutting away the front walls of the chamber and placing back of the opening thus formed a piece of glass 19 to prevent entrance of dirt to the chamber. The glass may be secured in the chamber by any suitable means, such as guides 19. The horizontal arms 20 are on the zero line 14 and preferably extend equal amounts on opposite sides of this line to assist in easily bringing this line into alignment with the horizontal hair of the level. The opposite ends of these arms are tapered, as shown at 21, and end in a small narrow slot 22 on the line. To assist in more properly positioning the rod I prefer to also provide vertical arms 23 at right angles to the horizontal line and similar to these arms.

In order that this cross may be easily visible in poor lights I provide means for illuminating it from the interior of the chamber. I prefer to use for this purpose an ordinary electric flash lamp indicated at 24. In the lower walls of the chamber is an opening for insertion of the light end of the lamp so that the light rays from the lamp are projected into the chamber thoroughly illuminating the cross, and means is provided for detachably securing this lamp to the target so that it may be easily applied and removed as desired. In Fig. 1 I have shown spring clips 25 on opposite sides of the lamp provided with offsets 26 adapted to engage between the grooves formed by the threads 27 on the cap of the lamp so that the lamp may be secured in position by merely forcing in the light end thereof to the position shown in Fig. 1, and it may be removed by merely pulling it downwardly. In Fig. 2 I have shown a threaded sleeve 28 surrounding the opening in the chamber to engage the threaded end of the casing of the lamp so that the lamp may be easily screwed into position or unscrewed therefrom. To insure proper illumination of the cross I prefer to provide a curved reflector 29 in the back wall of the chamber, and the inner surface of this reflector will preferably be painted a dull white. This reflector is, however, not necessary as the inner surface of the rear wall 30 may be painted a dull white if preferred. These light surfaces being illuminated by the lamp

the cross is clearly visible through the lens of the level. By having the arms of the cross extend on opposite sides of the zero line the horizontal hair of the level is clearly visible extending longitudinally of the horizontal arms of the cross as the light is on both sides of the hair, and it is very easy to determine when the target is in position to bring the horizontal line 14 over the 10 hair of the instrument. The vertical arms of the cross clearly show the vertical hair of the instrument in the same way, indicating whether the rod is held vertically. It is not necessary that the glass covering 15 the cross be clear as it may be ground glass, which will clearly show the threads of the instrument if illuminated from the rear. This device is clearly visible in all kinds of lights. The electric light may be easily applied or removed, and it is safe to use in all locations such as mines where there might be danger of an explosion from gas should an open light be used.

Having thus set forth the nature of my 25 invention, what I claim is:

1. A target adapted to slide on a graduated rod provided with a chamber at one side of said rod, a transparent cross in the front wall of said chamber having vertical and horizontal arms, and means for illuminating said cross.

2. A target for a leveler's rod provided on the front wall thereof with a cross having vertical and horizontal arms, and means for illuminating said arms.

3. A target for a leveler's rod provided on the front wall thereof with a cross having vertical and horizontal arms, said horizontal arms being tapered at the ends thereof with narrow slots leading from the ends of the tapers.

4. A target for a leveler's rod having a chamber, a cross in the front wall of said chamber having vertical and horizontal arms, said cross being adapted for transmission of light, and means within the chamber for illuminating the cross.

5. A target for a leveler's rod having a chamber, said target having a horizontal 50 zero line on the face of the front wall thereof a relatively narrow horizontal window in said front wall adapted for transmission of light and extending on both sides of said line, the ends of said window tapering toward said line, and means in the chamber for illuminating the window.

6. A target for a leveler's rod adapted for sliding adjustment on said rod and provided with a chamber at one side thereof, a transparent cross in the front wall thereof having vertical and horizontal arms, a light colored wall to the rear of said cross, and means for illuminating said wall.

7. A target for a leveler's rod adapted for sliding adjustment on said rod and provided with a chamber at one side thereof, said target having a horizontal zero line running across the face thereof, a cross in the front wall of said casing having horizontal arms extending on opposite sides of said line and provided with narrow slots in the ends of the arms in alignment with said line, said cross being adapted for transmission of light, and means in said chamber for illuminating said cross.

8. A target for a leveler's rod adapted for sliding adjustment on said rod and provided with a chamber at one side thereof, said chamber being provided in the front wall thereof with a cross adapted for transmission of light and having horizontal arms on the zero line of the target, an electric flash light for illuminating said cross, and means for detachably mounting said light in said target.

9. A target for a leveler's rod adapted for sliding adjustment on said rod and provided with a chamber at one side thereof, said chamber being provided in the front wall thereof with a cross adapted for transmission of light and having horizontal arms on the zero line of the target, the lower wall of said chamber being provided with an opening adapted for insertion of the light end of an electric flash lamp, and means for detachably securing an electric flash lamp in said opening to illuminate said cross.

10. A target for a leveler's rod adapted for sliding adjustment on said rod and provided with a chamber at one side thereof, said chamber being provided in the front wall thereof with a cross adapted for transmission of light and having horizontal arms on the zero line of the target and extending on opposite sides thereof, said arms being provided at their ends with narrow slots on said line, and means for detachably connecting an electric flash lamp to said target to project its light into said chamber and illuminate said cross.

In testimony whereof I affix my signature:
WILLIAM J. BARRETT.
